AGITATOR FOR WASHING MACHINES

Leland G. Knapp, Chicago, and Thomas V. Parke,
 Glen Ellyn, Ill., assignors to Montgomery Ward
 & Co., Incorporated, Chicago, Ill., a corporation
 of Illinois

Application October 11, 1935, Serial No. 44,482

4 Claims. (Cl. 68—134)

The present invention has to do with agitators for washing machines designed for the cleansing of clothes and like articles, and is directed to the improvement of the construction of agitator disclosed in and covered by Letters Patent of the United States No. 1,946,535, dated February 13, 1934, granted on the application of Leland G. Knapp.

The agitator of the patent referred to includes a plurality of radial vanes of defined contour or configuration and serves admirably for effecting the cleansing of soiled fabrics. In those tubs, however, that are of relatively narrow diameter, so that the top of the agitator is submerged to a considerable extent beneath the water line, it has been found that the clothes or other articles being cleansed will mass or ball at the agitator top and remain thereon. The clothes, therefore, are removed from the direct zone of agitation and are not subject to the action of the vanes as the latter move back and forth in the gyratory movement of the agitator.

The main and primary object of the present invention is the provision of means by which the massing or balling of the clothes at the top of the agitator is prevented and the clothes maintained in the zone of action of the agitator vanes to be acted thereon by the vanes.

A further object of the invention is to provide an improved agitator the operation of which materially changes the action of the water currents that is characteristic of the operation of the agitator of the patent aforesaid, with a resultant improvement in the washing action.

Other objects and advantages will appear as the nature of the improvements is better understood, the invention consisting substantially in the novel construction, combination and arrangement of parts hereinafter fully described, illustrated in the accompanying drawing and pointed out in the appended claims.

While the form of the invention herein shown and described is believed to be a preferred embodiment thereof, and delineates its practical application, it is to be understood that the same is to be considered from the illustrative standpoint and not as imposing restriction or limitation on the invention.

In the drawing:

Fig. 1 is a vertical transverse sectional view of a washing machine agitator constructed in accordance with the present invention and illustrated in its application to the tub of a machine;

Fig. 2 is a top plan view thereof;

Fig. 3 is a fragmentary detail elevation of the lower end of the agitator.

Referring in detail to the accompanying drawing, the numeral 10 designates the tub of a washing machine which is designed for cleansing clothes and like articles. It is provided at the center of its bottom 11 with a shaft bearing 12 through which a driving shaft 13 projects, the bottom 11 being suitably perforated for positioning the shaft bearing 12 therein. The upper end of the shaft 12 terminates in a tapered 10 splined head 14 by which driving connection is afforded between the agitator and the shaft 13.

The bottom 11 has at its central portion an inclined draining area 15.

The parts thus far described form no part of the present invention and are referred to only for a better understanding of the application of the herein-described agitator to the tub of the washing machine.

The agitator includes a relatively low base 16 which is circular in form, the top of said base being flat and horizontal. The base 16 includes an annular depending flange 17 at the edge of the flattened top of the base, and this flange is of such width that its free lower edge will lie close to the inclined draining area 15 of the bottom 11. This prevents the articles being cleansed from passing between the inclined area 15 and the lower edge of the flange 17 and entering the space within the base 16.

At appropriate points at the interior of the base 16 a series of radially extending strengthening ribs 18 is provided, these ribs being positioned in suitably spaced relation, preferably equi-distant, and thereby reinforcing the base 16. The ribs 18 extend from the flange 17 inwardly towards the center of the base, but their inner ends terminate short of the actual center of the base.

The flange 17 has a plurality of openings 19 formed therein in suitably spaced relation, which openings permit the water of the tub to pass into and out of the interior of the base, and thereby serve to keep the interior of the base 45 free from the accumulation of dirt, soap particles and other deposits that arise incidental to the washing of soiled fabrics.

At the center of the base 16 is located a vertically disposed supporting standard 20, which standard is tubular, and thereby provides a sleeve the lower end of the bore of which is in communication with the interior of the base 16. At the point of joinder of the lower end of the supporting standard 20 with the base 16 the metal 55

- of which the base and the standard are formed is massed in stepped formation, as at 21, so as to strengthen the lower end of the standard 20 at this point. The lower end of the bore of the standard 20 is provided with a tapered mouth, and this mouth is splined so that it may receive the splined head 14 of the drive shaft 13 in order to operatively connect the agitator with the drive shaft for operation of the agitator by the shaft.

That the agitator may be held in fixed engagement with the splined head 14 as described, an elongated fastening screw 22 is employed. The lower threaded end of this screw engages a threaded opening in the upper end of the splined head 14, the head of the screw being seated against the tapered upper end of the bore of the standard 20, which engagement binds the agitator into the operative relation with the splined head 14 referred to.

It will be understood that the movement of the drive shaft 13 is an oscillatory movement so as to impart to the agitator a similar or gyratory movement, in the manner that is characteristic of the present day gyratory washing machines.

Associated with the supporting standard 20, and formed integral therewith, as well as with the base 16, is a plurality of radially-extending vanes 23. The lower ends of the vanes 23 extend outwardly from the standard 20 to the peripheral edge of the flat top of the base 16. This lateral extension of the base of the vanes fills the space between the supporting standard 20 and the edge of the base 16 so as to present a relatively wide surface to the water for agitating the latter as the vanes move back and forth under the oscillatory movement of the drive shaft 13.

The outer edge of each of the vanes 23, commencing with the top surface of the base 16, is curved inwardly, as at 24, and then curves outwardly and upwardly, as at 25, to a point 26, and at this point each of the vanes is of its widest radial dimension. It will be observed also that this point of widest radial dimension is relatively high with respect to the total vertical dimension of the vane, and said point of widest radial dimension likewise is considerably above the medial point between the upper and lower extremities of the supporting standard 20. The effect of positioning the widest radial dimension of the vanes at the point indicated is to effect throw of the water outwardly from the vanes at a point that is well above the bottom of the tub, and likewise well above the flat top of the base 16 and into the zone of the direct washing action of the agitator on the fabrics being cleansed.

From the point 26 the edge of each of the vanes 23 is curved slightly upwardly and merges into an inwardly and upwardly inclined top 27, thus completing the outline or configuration of the vane.

The structure of the vanes 23 constituted as above described affords an exceedingly broad surface of contact for the water in the movement of the agitator, and this results in a high degree of turbulence in the water so as to force the latter into contact with and through the articles being cleansed.

As previously stated, it is one of the objects of the present invention to provide an agitator the operation of which materially changes the action of the water currents characteristic of the operation of the agitator of the Knapp Patent No. 1,946,535 to which reference has been made. In the action of vanes 23 the degree of agitation or turbulence of the water of the tub adjacent the

surface level thereof is very high, and the articles being cleansed have a tendency to rise and to be removed from the zone of the direct action of the vanes 23. To counteract this high degree of turbulence and the tendency of the articles to rise, the herein-described agitator is provided with a plurality of supplemental vanes 28 which are formed integral with the vanes 23 and are positioned at the top of these vanes. The supplemental vanes 28, considered from the standpoint of their greatest radial dimension, are considerably less in width than the vanes 23 considered from the standpoint of their greatest radial dimension. The contour or configuration of the supplemental vanes 28 follows generally the contour or configuration of the vanes 23. Commencing with the top edges 27 of the vanes 23 the lower ends of the free edges of the vanes 28 are curved inwardly, as at 29, and then curve outwardly and upwardly to a point 30, at which point each of the supplemental vanes 28 is of its widest radial dimension. From this point the top edge of each of the vanes 28 inclines to the end of the supporting standard 20 where it terminates and merges into that end of the standard 20.

In the action of the supplemental vanes 28 the water is thrown outwardly, and the creation of these outwardly flowing currents has the effect to counteract the turbulence of the water at the surface level of the latter. In so counteracting this turbulence the tendency of the articles being cleansed to rise upwardly from the zone of the direct action of the vanes 23 likewise is counteracted, and this results in holding the articles being cleansed at a point to be most effectively acted on by the vanes 23.

The vanes 23 are perforated, as at 31, to provide a plurality of openings therein to permit passage of the water in the back and forth movement of the vanes. This permits the vanes to move in the water under less power than if the vanes were wholly imperforate. At the same time as the water passes through these openings the effect of its cleansing action on the articles and penetration of the articles is enhanced.

The top of the base 16 is also provided with a plurality of perforations 32 to permit entrance and circulation of the water through the top of the base and within the interior of the latter. In cooperation with the openings 19 in the guard flange 17 it will be apparent that such circulation is easily maintained.

By referring to Fig. 2 it will be observed that at the points where the vanes join with the supporting standard 20 the adjacent surfaces of the vanes merge into each other on curved lines. This is effected by fillets 33 of the metal being massed at these points. This not only strengthens the points of connection of the vanes with the supporting standard, but it eliminates sharp angles between the vanes and gives a smooth surface to the metal at the points indicated. The fillets 33 extend throughout the length of the vanes 23 and also the vanes 28.

In the operation of the herein-described agitator the throw of each of the vanes, in each direction of its movement, is approximately 180°. Obviously, the greater radial dimension of the vanes 23 results in a high degree of turbulence in the water and effects the cleansing of the articles, the latter being moved backwardly and forwardly as the vanes move backwardly and forwardly. As the currents rise upwardly towards the surface level of the water the action of the supplemental vanes 28, in their throw of the water out-

wardly, counteracts such rising currents, and the tendency of the articles being cleansed to rise is counteracted by the action of the supplemental vanes 28, thus maintaining the articles 5 in the zone of the direct action of the vanes 23 so as to be effectually washed.

The supplemental vanes 28, in their superposed relation to the vanes 23, serve also to prevent massing or balling of the articles at the top 10 of the vanes 23, so that the agitator is free to operate in its path of movement, and is not impeded by the articles becoming entangled with the agitator at its upper end.

By referring to Fig. 2 it will be noted that the 15 strengthening ribs 18 are disposed at the interior of the base 16 at points which are opposite to the spaces between the vanes 23 at the exterior of the base. This facilitates the manufacture of the base and its vanes, and also distributes the 20 reinforcing effect of the ribs 18 at points within the interior of the base so as to obtain the effect of that reinforcement between the points of connection of the vanes 23 with the base at the outside of the latter.

25 The herein-described agitator preferably is formed of aluminum, but any other material may be used capable of resisting the action of the washing mixtures commonly employed in these machines.

30 We claim:

1. An agitator for a clothes washing machine, comprising a base, a supporting standard carried thereby and vertically-disposed thereon, a plurality of vanes arranged in radial relation to said standard, the greatest radial dimension of said vanes being greater than the greatest radial dimension of the base and located at a point above the medial point between the upper and lower extremities of said supporting standard, 35 and a plurality of supplemental vanes also arranged in radial relation to said standard and located in superimposed relation with and merging into the first mentioned vanes.

2. An agitator for a clothes washing machine, 40 comprising a base, a supporting standard carried thereby and vertically-disposed thereon, a plu-

rality of vanes arranged in radial relation to said standard, the greatest radial dimension of said vanes being greater than the greatest radial dimension of the base and located at a point above the medial point between the upper and lower 5 extremities of said supporting standard, and a plurality of supplemental vanes also arranged in radial relation to said standard and located in superimposed relation with and merging into the first-mentioned vanes and in vertical alignment 10 therewith.

3. An agitator for a clothes washing machine, comprising a base, a supporting standard carried thereby and vertically-disposed thereon, a plurality of vanes arranged in radial relation to said 15 standard, the greatest radial dimension of said vanes being greater than the greatest radial dimension of the base and located at a point above the medial point between the upper and lower extremities of said supporting standard, and a 20 plurality of supplemental vanes also arranged in radial relation to said standard and located in superimposed relation with and merging into the first-mentioned vanes, the greatest radial dimension of the supplemental vanes being less than 25 the greatest radial dimension of the first-mentioned vanes.

4. An agitator for a clothes washing machine, comprising a base, a supporting standard carried thereby and vertically-disposed thereon, a plurality of vanes arranged in radial relation to said standard, and a plurality of supplemental vanes also arranged in radial relation to said standard and located in superimposed relation to the first-mentioned vanes, the greatest radial dimension 35 of the first-mentioned vanes being greater than the greatest radial dimension of the base and located at a point above the medial point between the upper and lower extremities of said supporting standard, the greatest radial dimension 40 of the supplemental vanes being less than the greatest radial dimension of the first-mentioned vanes.
